Primary Examiner — T. Chase Nelson*Assistant Examiner* — Mark Cavanna(74) *Attorney, Agent, or Firm* — Olive Law Group, PLLC(57) **CLAIM**

We claim the ornamental design for the electrode patch array, as shown and described.

DESCRIPTION

FIG. 1 is a top view of an electrode patch array showing our new design;

FIG. 2 is a bottom view thereof;

FIG. 3 is a side view thereof;

FIG. 4 is an opposite side view thereof;

FIG. 5 is a front view thereof;

FIG. 6 is a back view thereof;

FIG. 7 is a top perspective view thereof; and,

FIG. 8 is a bottom perspective thereof.

The broken lines are included for the purpose of illustrating portions of the electrode patch array that form no part of the claimed design.

1 Claim, 3 Drawing Sheets(56)
